UNITED STATES PATENT OFFICE.

EDWARD COURT, OF WAKEFIELD, ENGLAND.

PROPELLION OF SHIPS.

1,161,453.

Specification of Letters Patent. Patented Nov. 23, 1915.

Application filed April 26, 1915. Serial No. 23,870.

To all whom it may concern:

Be it known that I, EDWARD COURT, a subject of the King of Great Britain and Ireland, residing at Wakefield, in the county 5 of York, England, have invented new and useful Improvements in or Relating to the Propulsion of Ships, of which the following is a specification.

This invention relates to the propulsion 10 of ships, more especially of the type in which a propeller shaft or pair of such shafts, extending from stern to stem of the ship and carrying at intervals a series of propellers, is or are inclosed within an open- 15 ended keel tube or channel, or pair of such keel tubes or channels, likewise extending from stern to stem of the ship.

My invention consists in the hereinafter 20 described improvements in this type of propelling device, characterized by the series 25 of inclosed or internal propellers being employed in combination with and auxiliary to the usual external propellers at stern and stem, and by the keel tube or propeller tube being of an enlarged diameter from the engine room to the stern of the ship, whereby 30 the effective area of the tube is maintained as it passes beneath and beside the lower part of the engine room, while at the same 35 time permitting of larger auxiliary propellers being fitted on the rear part of the shaft, and further characterized by the em- 40 ployment, at each end of the keel tube or propeller tube, of a watertight external sliding plug or cap (controlled by wheel, screw, and lever mechanism) for facilitat- 45 ing the pumping out of the tube for inspec- 50 tion and repairs in case of breakdown or injury to the shaft or propellers.

40 *Description of drawings.*—Figure 1 is a side elevation illustrating the application of my invention to a ship having twin propeller shafts. Fig. 2 is a diagrammatic plan of Fig. 1.

45 According to my said invention the propeller tube or tubes A is or are extended from stern to stem of the vessel, forming a keel tube or tubes open at both ends, and with the propeller shaft or shafts B likewise 50 extending from stern to stem. Each shaft B is fitted with the usual external main propeller C at the stern, and with a series of auxiliary propellers D within the keel tube. For instance one auxiliary propeller may be 55 fitted near the stem of the vessel, another

near the stern, and one or more at suitable intermediate points, five of these internal auxiliary propellers D being shown in the example illustrated. Each shaft is also fitted with an external propeller E at the 60 stem.

Each shaft B is supported on suitable thrust blocks F between each pair of propellers, the keel tube or propeller tube A having a series of suitably placed water- 65 tight manholes G for inspection of the thrust blocks and also for access to the propellers and shaft when desired. A suitable grid H is also fitted toward one or both ends 70 of the keel tube or propeller tube A.

75 Means are provided, comprising an external sliding plug or cap I controlled by a forked lever J actuated by wheel K and screw L from the deck or elsewhere, for closing each end of the tube A in case of break- 80 down or injury to the shaft or propellers, thus enabling the keel tube or propeller tube A to be pumped out for the necessary in- 85 spection and repairs. For this purpose a branch pipe or pipes M may be fitted behind the ordinary Kingston valve or seacock and connected to the keel tube or propeller tube A, so that (the seacock being first closed) 90 the pumps can draw direct from the tube or tubes A and thus (assisted by bilge and auxiliary pumps) facilitate the operation of emptying the tube or tubes, the engineer being notified when the emptying operation is completed by the immediate fall of the vacuum on the gage. The tube or tubes A 95 when empty will serve as a means of in- 100 creasing the buoyancy of the ship.

The keel tube or propeller tube A is of uniform diameter from the stem to the engine room N amidships, from which point 95 the tube is enlarged toward the stern of the ship, thus obtaining, in a cavity O beneath and beside the lower part of the engine room, the full area of the smaller or for- 100 ward end of the tube, and at the same time giving a quicker release and permitting of larger auxiliary propellers being employed from the engine room to the stern of the ship.

105 The keel tubes or propeller tubes as here- inbefore described also tend to strengthen and stiffen the ship, and at the same time to distribute the driving strain throughout the length of the ship, and to steady the vessel and maintain it on an even keel, especially 110

in heavy seas. The speed is also increased, fuel and power economized, and racing of the propeller shaft or shafts is prevented.

I claim:

- 5 1. Ship propelling devices comprising, in combination, an open-ended keel tube extending from stern to stem and being of an enlarged diameter from engine room to stern, a propeller shaft mounted in bearings within said tube and likewise extending from stern to stem, external main propellers at stern and stem upon said shaft, a series of internal auxiliary propellers upon said shaft within the narrower forward end of said tube, a series of larger internal auxiliary propellers upon said shaft within the wider stern end of said tube, substantially as herein set forth.
- 10 2. Ship propelling devices comprising, in combination, an open-ended keel tube ex-
- 15
- 20

tending from stern to stem and being of an enlarged diameter from engine room to stern, a propeller shaft mounted in bearings within said tube and likewise extending from stern to stem, external main propellers at stern and stem upon said shaft, a series of internal auxiliary propellers upon said shaft within the narrower forward end of said tube, a series of larger internal auxiliary propellers upon said shaft within the wider stern end of said tube, watertight external sliding plugs slideable on said shaft for closing the ends of said tube, and screw and lever devices for controlling said sliding plugs, substantially as herein set forth. 30 35

EDWARD COURT.
